SEPARABLE LIGHT BULB HUSK

Elliott I. Clemence, Millburn, N. J.

Application February 24, 1937, Serial No. 127,396

13 Claims. (Cl. 173—358)

The present invention relates to an improvement in electric lamp sockets or husks, and while primarily intended to be used for miniature electric lights of the decorative type, it is not limited 5 to such use.

The main advantage in the present construction is in the provision of a husk body made of two longitudinal half sections, which may be interfitting, and each of which sections may be 10 assembled to their respective coating conductive members while separated, and then assembled into a unified structure. This type of structure lends itself perfectly to extremely small husk bodies, and is convenient to assemble, and very 15 economical in manufacture without, in anyway affecting the utility or safety ordinarily required in husk sockets of this type.

The foregoing features of advantage and others will be apprehended as the herein description proceeds, and it will be obvious that modifications 20 may be made in the structure herein without departing from the spirit hereof or the scope of the appended claims.

In the drawing,

25 Fig. 1 is a longitudinal sectional view of an assembled two part husk, in elevation, taken on the line 1—1, Fig. 2, looking in the direction of the arrows;

Fig. 2 is a bottom view of the husk;

30 Fig. 3 is a view in elevation thereof with the husk of Fig. 1 rotated ninety degrees;

Fig. 4 is a bottom view of the husk clamp ring and snap clip, removed from the husk;

Fig. 5 is a view in elevation of one assembled 35 husk section;

Fig. 6 is a plan view thereof;

Fig. 7 is a view in elevation of the other assembled husk section;

Fig. 8 is a plan view thereof; and

40 Fig. 9 is a view in elevation of a husk section, disclosing interfitting locking means thereon.

As illustrated in Figs. 5 and 7, the husk body comprises two longitudinal dielectric, moulded half sections of similar semi-cylindrical outline, 45 generally indicated as 1 and 2.

Both sections, Fig. 1, have relatively upper lamp socket receiving halves 3—3, and lower enlarged base portions 5—5, each base portion being closed by half section webs 28 and 29 respectively.

50 The half section 1, Figs. 1, 2 and 6 has a plurality of integral lamp socket engaging threads, generally denoted by 4, moulded on the inner semi-circular face of its portion 3. These threads are discontinuous but are of proper pitch to non-

electrically engage the threads on a lamp base.

Section 1, further, is provided with a single piece, yieldable contact and conductor generally denoted by C, which is located to contact with the central contact of a light bulb. This contact and conductor, as in Figs. 1, 5 and 6, is made of sheet metal stamped to provide a conductor wall portion 30, which rests and is affixed upon the stepped chordal wall section 31, 33 of the husk section 1, the said conductor portion 30 being 10 provided with a resilient outstanding contact tongue 22, which is formed at substantially right angles to the conductor 30, and which resiliently contacts with central terminal of a light bulb.

The conductor 30 is provided at its lower end, 15 as viewed in Figs. 1 and 5 with a perforated, stamped out clamp tongue 13, and by means of a headed, snug fitted metal pin, or brad, 15, the conductor 30 is literally nailed to the face of the chordal wall 33, said wall being provided, in 20 moulding, with a pin bore, into which the brad is driven, as shown in Fig. 1. Before pinning the clamp tongue to the wall, the bared end 14 of a conductor wire 25, Fig. 5, is forced under the tongue 13, and the consequent nailing of the 25 conductor not only affixes the conductor-contact in position but also insures a tight contact about the wire end 14, as illustrated in Fig. 1. The conductor wire enters from the side of base 5, of the section 1 by means of a moulded in groove 30 24 fully shown in Fig. 5.

The other husk section 2, shown best in Figs. 1, 7 and 8, is very similar in construction to section 1, with the following exceptions; the inner face of the socket section 3 is without moulded-in 35 threads and there is substituted therefor a metallic conductor-contact, generally denoted by B, in a single piece, but stamped up to conform to the inner wall contour of the section. To this end there is a semi-cylindrical portion fitting the 40 lamp socket end 3, which has light bulb engaging threads 6 thereon, said threads being discontinuous helically, but of same pitch so as to engage the threaded end of a light bulb in electrical contact. The lower portion 7 of the conductor contact is formed offset, to fit across the chordal face 34 of the husk section base 5, by means of the offset web 35 which joins the threaded portion 6 to the conductor portion 7, Fig. 8.

Conductor portion 7, is, like conductor 30 of husk portion 1, provided at its lower end with a perforated, stamped and slotted out wire clamp tongue 8, under which the bared end of conductor wire 26 may be inserted and a headed 55

brad 10 tightly driven in through the perforation in tongue 8, into a pre-moulded hole in the chordal wall of base 5, as disclosed in Fig. 1, thus clamping tongue 8 tightly down over the 5 contact end of wire 26, and simultaneously firmly affixing the conductor-contact piece B firmly in operative position in portion 2. The contact wire 25 enters from the side of the base 5 through groove 23, moulded therein.

10 Above the web 35, which joins the threads 6 to the conductor portion 7, Fig. 8 is located a preferably triangular shaped aperture A, and through this aperture projects an extending dielectric pin, which is tightly driven into the wall 15 of the husk portion 2. This pin 11 extends to about the parting flat face of the husk portion 2, as illustrated in Figs. 1, 2 and 8, and is so located, as in Figs. 1 and 2, as to support by its outer end, the outer end of the resilient contact 20 22 of husk portion 1, when both portions are in assembled operative position, and as illustrated in Fig. 1. In practice the spring contact 22 is slightly upraised, and assumes the position of Fig. 1, when a light bulb is screwed into the assembled husk, and thus non-conductive pin 11 25 acts as a limiting stop for both contact 22 and the light bulb, and also prevents rotation of the conductor contact B, when screwing in a light bulb.

30 After the assembly of the two husk sections 1 and 2, as above described, they are then placed flat face to flat face as in Figs. 1 and 2 and tightly fitting metallic ring 16, Figs. 1, 3 and 4 is pressed downwardly over the socket sections 35 3-3 to the shoulder of base 5, Fig. 1, and thus the fixed assembly of the husk is completed.

40 In order to prevent inadvertent displacement of the husk closure ring 16, the ring is provided with a spring latch 19 therein, suitably affixed thereto at its nonoperative end 17, while its operative end is provided with an inturned ledge or catch 20, Figs. 1 and 3, for the purpose of snapping under the bottom of the base 1 when ring 16 is finally seated. This latch 19 prevents inadvertent removal of ring 16, but does not interfere with its removal for repair or other purposes.

45 The ring 16 may also support thereon the usual forked, spring-like tree-branch clips 50 18-18, as illustrated in Figs. 1 to 4 inclusive.

55 As a means to permit the interfitting of the flat faces of the husk portions to hold them in registry during assembly, there is disclosed, in Fig. 9, a husk section somewhat like 2, on the flat faces of the base portion of which are located raised beaded portions 27-27, these being traversed by the wire groove 23, and on the opposite side, the flat face is provided with an indent 26'. When two coacting husk portions are provided with indents and beads as described, and are then assembled face to face, the husk portions are then accurately interfitting by the coacting beads and lugs and are prevented from sliding out of normal assembly 60 65 position until the ring 16 is operatively positioned.

70 From the foregoing description, it will be noted that the assembly of the husk portions for very miniature light husks, due to the husk being in two parts, with the interiors thereof exposed, is easily accomplished, and further, the assembly of portion 1 creates a husk contact connection for the central contact of a light bulb, while the assembly of the portion 2 creates a contact 75 connection for the threaded outer ferrule contact

of a light bulb and thus these two sections may be assembled in mate groups and then brought together for final cooperative assembly, into completed husks.

Having thus described the invention what is 5 claimed is:

1. In combination, a shell having an upper cylindrical portion forming a cylindrical lamp thimble-receiving socket; the lower portion of said shell having a base forming a chamber 10 smaller in diameter than said socket and having a lower opening, a closed bottom wall and opposite side walls; conductor contacts respectively having downwardly extended flat portions engaged against the said walls respectively; the 15 lower mid margin of each flat portion being provided with upwardly extended slits and downwardly pointing tongue therebetween; conducting wires passing through said lower opening, under said tongues and over said margins respectively; pins passing through the lower part of the respective tongues into said walls and securing said wires and conductor contacts in place; the upper part of one conductor-contact being provided with an outstanding contact 20 25 tongue crossing the axis of the socket at the lower part thereof; the other conductor contact extending upwardly into the socket to engage the side of the lamp thimble.

2. In combination, a pair of similar longitudinal shell half sections having coacting faces meeting in an axial plane and together forming a cylindrical lamp-thimble-receiving socket; a portion of said sections forming a cylindrical exterior face and a base larger in diameter and forming an annular shoulder next to said exterior face; a ring fitting against said shoulder and on said exterior face and extending more than half way up the latter; means holding the ring and one member against relative longitudinal movement; and additional means holding the members against relative longitudinal movement.

3. In combination, a pair of similar longitudinal shell half sections having coacting faces meeting in an axial plane and forming a lamp-thimble-receiving socket; a portion of said sections forming a cylindrical exterior face and a base larger in diameter and forming an annular shoulder next to said exterior face; a ring fitting against said shoulder and on said exterior face and extending more than half way up the latter; and a hook carried by the ring and engaging against the end face of the shell at the base.

4. In combination, a pair of similar longitudinal shell half sections having coacting faces meeting in an axial plane; the upper portion of said sections together forming a cylindrical lamp-thimble-receiving socket; the lower portion of said sections forming a base and having recesses forming a chamber; a pair of conductor-contacts having portions for engaging said thimble and portions secured against walls of said chamber; conducting wires passing to said contacts; the upper portions of said sections forming a cylindrical exterior face, the base being larger in diameter and forming an annular shoulder below said exterior face; a deep cylindrical ring fitting against said shoulder and on 70 said exterior face; and a flat spring latch member having a yoke secured around a portion of the ring and provided at its mid part with a downwardly disposed spring latch yieldably engaging the side of the base and provided with an 75

5. In combination, a pair of separable longitudinal shell sections having longitudinal coacting faces and forming a shell having a lamp-receiving socket; a portion of said shell forming an exterior face and a shoulder next to said exterior face; a ring fitting against said shoulder and on said exterior face and holding the sections together; and a member secured to the ring and provided with a downwardly disposed latch provided with an inturned hook having its end portion yieldably releasably engaged against the lower end face of the shell substantially at right angles to the axis of the shell; said member being adapted to carry an upwardly disposed portion extending upwardly and then downwardly to form a branch-engaging clip; said latch having the multiple function of releasably preventing the rise of said ring and clip relative to the shell, thereby to releasably prevent the separation of said sections, and to resist the force tending to separate the ring from the shell when the shell is hanging by the clip.

6. A device for supporting a shell comprising a pair of separable longitudinal shell sections having longitudinal coacting faces and forming a lamp-receiving socket, a portion of said shell forming an exterior face and a shoulder next to said exterior face, and a ring fitting against said shoulder and on said exterior face and holding the sections together; said device comprising a member secured to the ring and provided with a downwardly disposed latch provided with an inturned hook having its end portion yieldably engaged against the lower end face of the shell substantially at right angles to the axis of the shell; said member carrying an upwardly disposed portion extending upwardly and then downwardly to form a branch-engaging clip; said latch having the multiple function of releasably preventing the rise of said ring and clip relative to the shell, thereby to releasably prevent the separation of said sections, and to resist the force tending to separate the ring from the shell when the shell is hanging by the clasp.

7. In combination, a pair of similar longitudinal shell half-sections having coacting faces meeting in an axial plane and forming a shell having a lamp-thimble-receiving socket; a portion of said sections forming a cylindrical exterior face and a base larger in diameter than the base and forming an annular shoulder next to said exterior face; a ring fitting against said shoulder and on said exterior face and extending more than half way up the latter and holding said sections together; a flat spring latch member having a yoke secured around a portion of the ring and provided at its mid part with a downwardly disposed spring latch provided with an inturned hook yieldably releasably engaged against the end face of the shell at the base; the ends of said yoke being provided with upwardly disposed portions extending upwardly and then turned downwardly and extending to the lower part of the latch to form spring like branch-engaging clips; said spring latch having the multiple function of preventing the lowering of said shell relative to said ring and clips as a result of pull on the shell when the shell is hanging by the clip, thereby to prevent the release of the ring from said face and the separation of said sections.

8. In combination, a ring; a latch member secured to the ring and provided with a downwardly

disposed spring latch provided with an inturned hook having its end substantially at right angles to the axis of the ring; said member being provided with an upwardly disposed portion extending upwardly and then downwardly to form a 5 branch-engaging clip.

9. In combination, a shell having an upper lamp-thimble-receiving socket; the lower portion of said shell having opposite side walls; conductor contacts having upper lamp thimble engaging contacts and lower flat portions engaged against the said walls respectively; a margin of each flat portion being provided with slits forming a tongue therebetween; conducting wires passing under said tongues and over said margins respectively; and pins passing through the lower part of the respective tongues into said walls and having the multiple function of tightening the edges of said slits against said conductors, securing said wires and tongues in place and assisting in positioning the contacts relative to the socket and thimble.

10. In combination, a shell having an upper portion forming a lamp thimble-receiving socket; the lower portion of said shell having a base 25 forming a chamber having a lower opening, a closed bottom wall and opposite side walls; conductor contacts having upper lamp thimble engaging contacts and downwardly extended flat portions engaged against the said walls respectively; the lower mid-margin of each flat portion being provided with upwardly extended sharp-edged slits forming a downwardly pointing tongue therebetween; conducting wires passing through said lower opening, under said tongues 35 and over said margins respectively; and pins passing through the lower part of the respective tongues into said walls and having the multiple function of tightening said sharp edges against said conductors, securing said wires and tongues 40 in place and aiding in positioning the upper parts of said contact in position relative to the socket and thimble.

11. In combination, a shell having an upper lamp-thimble-receiving socket; the lower portion of said shell having a chamber having opposite side walls; conductor contacts respectively having downwardly extended portions engaged against the said side walls respectively; securing means for securing said extended portions in place; conducting wires secured to said portions respectively; the upper part of one conductor contact being provided with an outstanding contact tongue to engage the axial contact of the lamp; the other conductor contact being upwardly extended to the side of the socket and provided with current-conducting threads to engage the side of the lamp thimble; the upper part of the extended portion of said other conductor-contact being provided with a small opening; a dielectric pin mounted in the adjacent wall and passing through the opening and disposed under the contact tongue.

12. In combination, a shell having an upper cylindrical socket having lamp-thimble-receiving threads at one side; the lower portion of said shell having a chamber having opposite flat side walls; conductor contacts respectively having downwardly extended flat portions engaged against the said side walls respectively; securing means for securing said flat portions in place; conducting wires secured to said portions respectively; the upper part of one conductor contact being provided with an outstanding contact tongue crossing the axis of the socket at the 75

lower part thereof to engage the axial contact of the lamp; the other conductor contact being upwardly extended to the side of the socket and provided with conducting threads opposite to said first named threads, and cooperating therewith to engage the side of the lamp thimble; the upper part of the flat portion of said other conductor-contact being provided with a small opening; a dielectric pin mounted in the adjacent wall and passing through the opening and disposed under the contact tongue, and adapted to resist depressing force on said tongue and upward lifting force on said conducting threads when the lamp is screwed tightly in place, thereby to cause said forces in part to neutralize each other and take strain from said securing means.

13. In combination, a pair of similar longitudinal shell half-sections having coating faces meeting in an axial plane; the upper portion of said sections together forming a lamp-thimble-receiving socket; the lower portion of said sections forming a base and having recesses form-

ing a substantially rectangular chamber having a closed bottom wall and opposed side walls having rectangular faces parallel to said plane and limited by chamber corners forming shoulders parallel to the shell axis; a pair of conductor-contacts having upper portions for engaging said thimble and lower flat portions secured against faces and having parallel side edges engaging said shoulders, and a lower portion near said bottom wall, said shoulders and bottom wall serving to position the contacts relative to said socket; said sections being provided at said faces with a pair of coating grooves forming an opening at the lower part of said chamber; conducting wires passing through said opening and secured to said contacts; means for securing said flat portions flat against said faces; and means for detachably securing said sections in assembled relation whereby said sections may be separated for securing said flat portions against said faces and shoulders.

ELLIOTT I. CLEMENCE.
